G. S. SCHVETZ

FOLDING STEEL SQUARE AND PROTRACTOR

Filed April 13, 1926

31 INVENTOR
George S. Schwetz
BY ATTORNEY

UNITED STATES PATENT OFFICE.

GEORGE S. SCHVETZ, OF NEW YORK, N. Y.

FOLDING STEEL SQUARE AND PROTRACTOR.

Application filed April 13, 1926. Serial No. 101,684.

This invention relates generally to squares such as used by machinists, millwrights, carpenters and the like, the invention having more particular reference 5 to a novel type of square. The invention has for an object the provision of an improved square of simple construction and arrangement of parts. For the comprehension of the invention, and of the objects and 10 advantages thereof, reference will be had to the following description and accompanying drawing, and to the appended claims in which the various novel features of the invention are more particularly set forth.

Fig. 1, of the drawing, is a top plan view of my improved square.

Fig. 2 is a side elevational view thereof.

Fig. 3 is a fragmentary top view, illustrating a modification of my improved square.

Fig. 4 is an enlarged sectional view taken on the line 4—4 of Fig. 3.

Fig. 5 is an enlarged fragmentary view showing the adjustable attaching means as used in combination with the modification 25 of my improved square.

As here embodied my improved square comprises a main member 10 grooved or notched, at both sides of one extremity, as at 11, to engage the movable member 12, 30 which is provided with an elongated aperture 13, located at the center of one extremity thereof. It being understood that the movable member 12 is pivotally attached to the said main member 10, as at 14, by 35 a screw, bolt, or the like so as to permit the said movable member to be pivoted as designated by the dot and dash lines 15, Fig. 1, of the accompanying drawing and to be used as a protractor in conjunction

40 with scale 24 on the movable member 12 and coacting scale 26 on the main member 10.

Referring in particular to Figs. 3, 4 and 5, of the accompanying drawing, in which I have illustrated a modification of my improved square, the above mentioned movable member 12 has slidably attached thereto, as at 27, by a dovetail tongue, adapted to slidably engage a dovetailed recess 28, formed in the movable member 12, a supplementary 45 member 17, depending therefrom and parallel to the main member 10. The supplement-

ary member 17 has attached thereto, as at 29, a spring 30, depending downward therefrom, and provided with an enlarged extremity 31 adapted to engage serrations 55 32 or teeth cut or otherwise formed in the recess 28, as a means of holding the supplementary member 17 in any desired relative extended position in the recess 28. The supplementary member 17 being grooved 60 or notched at both sides of its extremity, as at 18, to engage a second movable member 19, which is provided with an elongated aperture 20, located at the center of one extremity thereof, it being understood that 65 the second movable member 19, is pivotally attached to the said supplementary member 17, as at 21, by a screw, bolt, or the like, so as to permit the said second movable member 19 to be pivoted as designated by 70 the dot and dash lines 22.

It will be further understood that the main member 10, the movable member 12, the supplementary member 17, and the second movable member 19, are provided with 75 graduations 23, adjacent to the sides thereof, preferably in inches and fractions thereof, suitably engraved, etched, or otherwise affixed thereto.

It will also be understood that the movable member 12, and the second movable member 19, are provided with graduations 24, adjacent to the curved portions 25, in degrees, and minutes, and the member 10 and the supplementary secondary member 85 17, are provided with graduations 26, adjacent to the curved portions 25, so as to provide a scale, or adjustment for the said movable member 12, and the said second movable member 19.

It will be further understood that my improved square may be made of any suitable material, preferably steel, and in any suitable size such as may be desired by artisans of all trades using a square of this description.

Having thus described my invention, what I claim as new, and desire to protect by Letters Patent of the United States is as follows:—

In a device of the class described, a main member grooved at both sides of one ex-

tremity, a movable member pivotally attached to said main member, and formed with a dovetailed recess, a supplementary main member formed at one end with a dovetail tongue engageable in said dovetailed recess, a spring depending from said supplementary main member, serrations

formed in said dovetailed recess, and said spring being formed with an enlarged extremity engageable against said serrations. 10
In testimony whereof I have affixed my signature.

GEORGE S. SCHVETZ.
